UNITED STATES PATENT OFFICE.

WILLIAM VETTER, OF CINCINNATI, OHIO.

DESIGN FOR A MEDAL OR SIMILAR ARTICLE.

SPECIFICATION forming part of Design No. 31,964, dated December 12, 1899.

Application filed November 6, 1899. Serial No. 736,047. Term of patent 3½ years.

To all whom it may concern:

Be it known that I, WILLIAM VETTER, a citizen of the United States, residing at Cincinnati, in the county of Hamilton and State of Ohio, have invented and produced a new and original Design for a Medal or Similar Article; and I do hereby declare the following to be a full, clear, and exact description of the same, reference being had to the accompanying drawings, which form a part of this specification.

In the aforesaid drawings, Figure 1 shows an obverse side of a medal or similar article embodying my design, and Fig. 2 shows the reverse side of said medal.

The aforesaid medal or similar article is a disk showing on its obverse side a representation of an iron-clad war vessel similar to the *Maine*, while the reverse side of said medal shows bust portraits representing Dewey, 20 Miles, Shafter, and Sampson.

I claim as my invention—

The design for a medal or similar article as herein shown and described.

In testimony whereof I affix my signature 25 in presence of two witnesses.

WILLIAM VETTER.

Witnesses:

JAMES H. LAYMAN,
M. W. CONWAY.
